(57) **CLAIM**

The ornamental design for an animal feeder as shown and described.

DESCRIPTION

FIG. 1 is a top perspective view of an animal feeder showing my new design;

FIG. 2 is a front view thereof;

FIG. 3 is a right-side view thereof;

FIG. 4 is a rear view thereof;

FIG. 5 is a left-side view thereof;

FIG. 6 is a top view thereof; and,

FIG. 7 is a bottom view thereof.

The broken lines in the drawings depict portions of the animal feeder that form no part of the claimed design.

1 Claim, 7 Drawing Sheets
